UNITED STATES PATENT OFFICE.

CHARLES L. DAVIS, OF DETROIT, MICHIGAN, ASSIGNOR, BY MESNE ASSIGNMENTS, TO
A. MILLER BELFIELD AND JOHN P. MENTZER, TRUSTEES, OF CHICAGO, ILLINOIS.

AUTOMATIC MUSICAL INSTRUMENT.

1,169,132.

Specification of Letters Patent. Patented Jan. 25, 1916.

Application filed February 23, 1907. Serial No. 358,823.

To all whom it may concern:

Be it known that I, CHARLES L. DAVIS, a citizen of the United States, residing at Detroit, in the county of Wayne and State 5 of Michigan, have invented a certain new and useful Improvement in Automatic Musical Instruments, of which the following is a full, clear, concise, and exact description, reference being had to the accompanying 10 drawings, forming a part of this specification.

My invention relates to mechanical musical instruments, and especially to automatic instruments commonly known as inside 15 piano players or player pianos.

Prominent objects of the invention are, to provide a simple, practical, novel and advantageous metal action therefor; to simplify the same as much as possible; to secure 20 quick and effective operation of the piano keys; and to accomplish the foregoing and other desirable objects in a simple and expeditious manner.

In the accompanying drawings, Figure 1 25 is an end elevation of a player piano embodying my invention, with a portion of the case cut away for convenience of illustration; Fig. 2 is a front elevation of the same with the larger part of the front of the case 30 removed; Fig. 3 is a cross section of a portion of the piano, showing the piano key and action, the player action, and part of the piano case; Figs. 4 and 5 are respectively a plan view and cross section of a portion of 35 one section of the metal action; Figs. 6 and 7 are respectively a front elevation and a cross section of the portion of the mechanism for controlling the playing; and Fig. 8 is a view in side elevation of the pedal and 40 bellows mechanism.

Referring to the drawings, and especially to Fig. 1, I have shown a player piano having a piano case 1 containing a piano action 2 operated by keys 3. The pneumatic action 45 for operating the piano action 2 is arranged above the keys 3 and consists of a metal action whose general construction is set forth and claimed in application of mine Serial No. 271,408, filed July 27, 1905. As 50 utilized in this player piano, the action consists of three metal trays or casings 4, 4 (Figs. 2, 3, 4 and 5) each of which is supported at its ends by blocks 5, 5 secured to

hangars 6, 6 which are suspended from a cross supporting board 7 which extends 55 across the piano and is secured at its ends to the ends of the case by blocks 8 (Fig. 2). Thus the trays or casings 4, 4 extend substantially across the width of the piano. These casings or trays are provided with 60 primary and secondary valve mechanisms shown in Figs. 3, 4 and 5 embodying the general principles of construction and operation shown in my said other application. The present construction embodies certain 65 structural improvements over the arrangements shown in my said other application, and these, together with other matters, I desire to claim in my present application.

The trays or casings referred to are conveniently constructed of two substantially flat metal strips 9, 10 (Fig. 5), secured together as by soldering so as to form pneumatic passages or windways which are connected with the bellows or other wind-inducing apparatus, by a wind pipe 11 (Fig. 1). Each tray or casing is provided with a series of primary valve mechanisms 12, arranged along one side of the tray or casing, and also with a series of secondary valve 70 mechanisms 13 arranged along the other side thereof. The primary valve mechanisms comprise metal thimbles 14 extended up through apertures in the upper metal strip or sheet forming the top of the casing and 75 having threaded connection therewith, and metal caps 15 threaded upon the thimble 14. A valve stem 16 is provided with valves 17 and 18, the latter being adjustable by 80 threaded connection with said stem and also 85 with an end piece 19. The thimble 14 is provided with an aperture 20 forming an air port controlled by the adjustable valve 18, and the thimble 14 with an aperture 21 forming a vacuum port controlled by the 90 valve 17.

The bottom of the tray or casing 4 is provided with an annular downwardly projecting rim 22 forming an opening below the primary valve for the pouch 23 therefor. This pouch is held in position by a washer 24 which is secured in place by a pouch disk 25 having a lip 26 which extends up outside of the rim 22 and which is held in position by a ring 27 arranged to 100 slide on pins 28 and held firmly in position 105

thereon by nuts 29, 29. The pouch 23 is provided with a pad 30 below the head 19 on the valve stem 16. The secondary valve mechanism comprises a projection 31 formed 5 up on the top of the tray or casing 4 and having ports 32, 32 controlled by the secondary valve. A cylindrical piece 33 is mounted upon the projection 31 and has its lower end screw-threaded thereon. A 10 cap 34 has a threaded connection with the upper end of the cylinder 33 and is separated therefrom by a washer 35. The cap 34 has an aperture 36 forming an air port and a bridge 37 permanently secured to said 15 cap as by soldering. The secondary valve 38 is mounted within the housing formed by the cylinder 33 and cap 34 and has its lower end provided with a stem 39 carrying a head 40, and its upper end provided with a stem 20 41 carrying a head 42 desirably made of wood, and having a threaded connection with the stem 41. The bridge 37 forms a 25 guide for the head 42. A metallic tube 43 is secured to the cylindrical casing 33 as 25 by soldering. Below the secondary valve is a pouch 44 held by a pouch disk 25' of the same construction, and secured in position by the same devices as the pouch disk described in connection with the primary 30 valve mechanism.

A tube 46 is connected with the cap 15 of the primary valve, by a flexible rubber connection 47, and extends to the secondary pouch disk 25'. Tracker-board tubes 48, 48 35 run to the pouch disks 25, 25 of the primary valve mechanisms.

The operation of this valve mechanism is in accordance with the usual double pneumatic mechanism, the primary valve 17, 18 40 being lifted by the pouch 23 when the latter is elevated by the admission of air into a tracker board tube 48, and the primary valve in turn closing the vacuum port 21 and opening the air port 20 so as to permit air to 45 pass through the connecting tube 46 to the secondary pouch board 25' and thereby elevate the secondary pouch 44 and so lift the secondary valve 38 and close the air port 36 and open ports 32 and exhaust air from 50 the pneumatic tube 43.

The adjustment of the primary valve 18 upon its valve stem 16 is permitted when the valve is in position after the mechanism has been assembled, and also at any time 55 after the instrument has been put into use by turning the valve 18 relatively to the spindle 16. This permits a perfect adjustment of said valve relatively to the pouch 23. Also the secondary valve 38 can be adjusted 60 by adjusting its spindle 41 in the head 42. These advantageous features of construction are described and claimed in another application of mine, Serial No. 353,995, filed January 25, 1907.

65 The tracker board tubes 48, 48 run up to

a tracker board 50 (Fig. 2) conveniently mounted in the upper part of the piano case. Above the tracker board 50 is the music spool 51, and below it, the take-up roll 52, which are of the usual construction and operated by the usual forms of mechanism, which will not be described herein.

The tubes 43, 43 leading from the secondary valve mechanisms on the trays or casings 4, 4, are connected with pneumatics 53, 53 which extend back and are provided with reciprocating rods 54, 54 which work up and down in a guide strip 55, the latter being held in position by supports 56 secured to the top board or support 7. The rods 54 80 are provided at their upper ends with heads 58 which are arranged below and adapted to strike against the whippens 59 of the piano action. Thus the collapse of the pneumatics 53 by the exhaustion of air from them, causes 85 the elevation of the corresponding rods 54 whose heads 58 strike the whippens 59 and thereby actuate the piano action. The rods 54, 54, are made adjustable relatively to the pneumatics 53, 53, by adjusting nuts 60, 60 (Fig. 3), so as to permit adjustment of the rods relatively to the piano action.

The motor 61 for driving the take-up roll 52, and the music head 62 carrying the roll 51 and spool 52, are all mounted upon 95 the support 7 so that this support can be removed from the piano, and when so removed, will take with it the entire pneumatic action,—the music head, motor and driving apparatus, and thus permit free access to the piano mechanism in a very easy and convenient manner.

At the front of the piano, and below the keyboard thereof, are controlling levers 63, 64, 65, whereof the lever 63 is for operating 105 the loud pedal of the piano, the lever 64 for controlling the motor tempo, and the lever 65 for controlling the rewind apparatus. Depressible levers 66, 66 are also arranged at the front of the piano, and adapted to 110 control different sections of the action, the latter being divided so that its treble and bass are supplied with wind independently, and these two sections controlled by the two levers 66, 66. For this purpose controllers 115 67, 68 are provided, one for the bass and one for the treble, but as these controllers form no part of the invention claimed in this application, they will not be described herein.

The levers 63, 64, 65 and 66 are led to the front edge of the keybed 70 and mounted upon a hinged support 71 (Figs. 1, 6 and 7) which is arranged to fold up into position in front of said keybed, the levers being jointed at 72 to permit their forward ends to be swung up with the shelf 71. Thus the operating levers can be concealed from view, or exposed for use, by simply raising and lowering the shelf 71. This 120 125 130

construction is made the subject-matter of a separate application, Serial No. 353,996, filed January 25, 1907.

The bellows 73 is arranged in the lower part of the piano case, and operated by foot pedals 74. These latter are arranged so that they can be lifted bodily and swung into the inside of the piano case without detaching them. To such end these pedals are 10 pivotally connected with the front end of rods 75, 75 whose rear ends are pivoted at 76 to a base rail 78. Links 79 are pivotally connected with the upper ends of the pedals, and also connected to braces 77 on the bellows. In operating the pedals, the rods 79, 79 will expand and collapse the bellows, and when desired to place the pedals inside of the case, they are lifted up and swung back into the case as shown in Fig. 8.

20 It will be understood that changes and modification can be made without departing from the spirit of the invention.

What I claim is:—

1. A pneumatic action comprising a flat horizontally disposed metallic tray serving as a wind trunk, valve casings arranged upon the top of said wind trunk, and pouch supporting devices suspended from the bottom of the same, and a series of striking pneumatics extending from the edge of said tray in the direction of the width thereof.
2. The combination of a tray having holes in its bottom for pouches, pouches for said holes, pouch disks arranged below said holes, pins secured to and extending down through from the bottom of the tray, a supporting member for each pouch disk supported by said pins, and extending cross-

wise of the same and engaging said pouch disks and valve mechanisms controlled by 40 said pouches.

3. A pneumatic action comprising a casing or tray forming a pneumatic passage or windway, said tray having an elevated projection 31 formed thereon, a cylindric casing 33 having a threaded connection with said projection 31, which latter is adapted to form a valve seat, a valve 38 confined within said casing 33, and a cap 34 having a threaded connection with the casing 33 50 and carrying a guideway for said valve.

4. A pneumatic action comprising a casing or tray forming a pneumatic passage or windway, said tray having an elevated projection 31 formed thereon, a cylindric 55 casing 33 having a threaded connection with said projection 31, which latter is adapted to form a valve seat, a valve 38 confined within said casing 33, and a cap 34 having a threaded connection with the cas- 60 ing 33 and having a bridge 37 to form a guideway, and said valve 38 having a valve stem 39 provided with an adjustable head 42 fitted in said bridge 37.

5. In a pneumatic action, a pouch-holding 65 cup 25, a ring 27 engaging the outer edge of said cup, pins 28 with nuts 29 for holding said ring in place, and a valve mechanism under the control of said pouch.

In witness whereof, I hereunto subscribe 70 my name this 15th day of December, A. D., 1906.

CHARLES L. DAVIS.
